(57) **CLAIM**

The ornamental design for an oral device, as shown and described.

DESCRIPTION

FIG. 1 is a perspective view of a first embodiment of an oral device;

FIG. 2 is a front view of the oral device shown in FIG. 1, with a rear view being a mirror image thereof;

FIG. 3 is a right side view of the oral device shown in FIG. 1, with a left side view being a mirror image thereof;

FIG. 4 is a top view of the oral device shown in FIG. 1; and,

FIG. 5 is a bottom view of the oral device shown in FIG. 1. The dashed broken lines showing holes in FIGS. 1 and 3-5 are for environmental purposes only and do not form any part of the claimed design.

1 Claim, 1 Drawing Sheet# US D838,368 S
